UNITED STATES PATENT OFFICE.

JOHN C. EBERLE AND BENJAMIN STORCH, OF NEW YORK, N. Y.

MEANS FOR FORMING CONCRETE COLUMNS.

1,231,342.

Specification of Letters Patent. Patented June 26, 1917.

Application filed November 20, 1916. Serial No. 132,370.

To all whom it may concern:

Be it known that we, JOHN C. EBERLE and BENJAMIN STORCH, citizens of the United States, and residents of the city of New 5 York, in the county of Kings and New York, respectively, and State of New York, have invented certain new and useful Improvements in Means for Forming Concrete Columns, of which the following is a specification.

The present invention relates to improvements in molds for forming concrete supporting-columns.

Molds for this purpose have heretofore 15 been generally in use. All of the same, however, as far as known, have a number of serious defects. One of these defects consists in that the molds are not properly supported in position for the molding operation. On the other hand, if supporting 20 means are provided, the constructions are to such an extent complicated that they are impracticable for ordinary building work.

The main object of the present invention 25 is to provide a column-mold that is adapted to be supported by simple and inexpensive means, thereby obviating the difficulties experienced with constructions of this type heretofore in use.

Another object of the invention is to so 30 construct the supporting means that it can be easily taken apart after the molding operation, and used over and over again.

A further object of the invention is to 35 generally simplify and improve the construction of column molds, and to produce a commercial article, that is to say a device which can be manufactured at a cost that is not beyond that of those now generally adapted.

With these and other objects in view, 40 which will more fully appear as the nature of the invention is better understood, the same consists in the combination, arrangement, and construction of parts hereinafter 45 described, pointed out in the appended claims and illustrated in the accompanying drawings, it being understood that many changes may be made in the size and proportion of the several parts and details of 50 construction within the scope of the appended claims without departing from the spirit or sacrificing any of the advantages of the invention.

One of the many possible embodiments of

the invention is illustrated in the accompanying drawings, in which:

Figure 1 is a front elevation of a concrete column-top, formed by means of the mold herein disclosed; Fig. 2 is a central vertical section taken through the top part of the 60 mold; Fig. 3 is a top plan view of the mold and the elements co-operating therewith; Fig. 4 is a central vertical section taken through a detail of construction, on a larger scale; Fig. 5 is a top elevation of the detail 65 shown in Fig. 4; Fig. 6 is a front elevation of a portion of the mold; and Fig. 7 is a section taken on line 7-7 of Fig. 6.

Referring now to the drawings, the numeral 10 indicates a mold or casing for the 70 top or head of a round column. This mold is made of a plurality of longitudinally separable sections, for instance two sections 11 and 12, the edges of which overlap, as clearly shown at 13. The sections are united 75 by screw-bolts 14 or other fastening means. The mold is made of sheet iron or similar material, and is provided at its upper edge with an outwardly extending annular flange 15. For the purpose of supporting this 80 mold, there is an ordinary scaffolding 16 built. This scaffolding includes horizontally extending beams 17, which are so arranged as to form a square, into which the mold is 85 fitted. In the corners of the square are located struts 18, which connect intersecting beams 17. Above the upper faces of the beams 17 and struts 18 projects, within the square, a ring 19, of any suitable cross-section. In the case illustrated the ring 19 is 90 of a cross-section corresponding to that of an angle-iron, the horizontal flange 20 of which projects inward, that is to say toward the center of the ring. The ring is supported upon the scaffolding by a plurality of blocks 21. Each of these blocks is, preferably, made of two sections, denoted by the numerals 22 and 23. The sections 22 may be of any suitable configuration and are attached to the beams 17 or struts 18, 100 as the case may be, by nails 24 or otherwise. The vertical flange 25 of the ring 19 rests upon the sections 22 of the blocks, while the horizontal flange is supported by the substantially wedge-shaped sections 23 of the 105 blocks. The sections 23 of the blocks are attached to the sections 22 and to the beams 17 and struts 18 by nails 26, or by other suit-

able fastening means. Inasmuch as the inner face of the flange 25 of the ring abuts against the block sections 23, the said ring is held fixedly in position upon the scaffolding.

5 ing.

The operation of this device is as follows: In erecting the column mold, first the scaffolding 16 is built. The blocks 21 are then attached to the beams 17 and struts 18 there-
10 of. After this operation, the supporting ring 19 is placed in position, the ring being inserted from above the scaffolding. The column-top mold 10 is then inserted from above, whereby its flange 15 will rest upon
15 the ring 19. The wedge-shaped sections 23 of the blocks 21 are of such dimensions as to center the mold 10 in relation to the scaffolding, as appears clearly from Figs. 2 and 4 of the drawings, the inner top edges of the
20 block sections 23 abutting against the column mold, thereby holding the latter in position against lateral shifting. Ceiling mold plates 27 are then placed upon the scaffolding. These plates are secured to the
25 scaffolding in any suitable manner and extend to the supporting ring 19. The operator proceeds then with the molding operation in the usual manner, pouring the concrete 28 into the mold 10 and on the top
30 of the ceiling mold plates 27.

After the column and ceiling have properly set, the blocks 21 are removed from the scaffolding, permitting the supporting ring 19 to drop. The bolts 14 are then, by
35 means of a hammer or other suitable instrument, broken, thereby allowing the sections of the mold 10 to be taken apart and removed from the finished column.

What we claim is:

40 1. The combination with a scaffolding, of a sheet metal mold shaped to form the top

of a column, said mold being provided with an outwardly bent flange at its upper edge, and a supporting ring upon said scaffolding upon which said flange rests.

45

2. The combination with a scaffolding, of a sheet metal mold shaped to form the top of a column, said mold being provided with an outwardly bent flange at its upper edge, blocks attached to said scaffolding, and a supporting ring carried by said blocks, the flange of said mold resting upon said ring.

50

3. The combination with a scaffolding, of a sheet metal mold shaped to form the top of a column, said mold being provided with an outwardly bent flange at its upper edge, blocks attached to said scaffolding, and a supporting ring carried by said blocks, the flange of said mold resting upon said ring and said blocks abutting against the outer face of said mold.

55

4. The combination with a scaffolding, of a sheet metal mold shaped to form the top of a column, said mold being provided with an outwardly bent flange at its upper edge, a supporting ring, and means for fixing said ring in position upon said scaffolding, the flange of said mold resting upon said ring.

60

5. The combination with a scaffolding, of a sheet metal mold shaped to form the top of a column, said mold being provided with an outwardly bent flange at its upper edge, a supporting ring, and means for fixing said ring in position upon said scaffolding, the flange of said mold resting upon said ring and said fixing means abutting against the outer face of said mold.

65

Signed at New York, in the county of New York, and State of New York, this 14th day of November, A. D. 1916.

JOHN C. EBERLE.
BENJAMIN STORCH.
